UNITED STATES PATENT OFFICE.

JOHN F. ROBB, OF CLEVELAND HEIGHTS, OHIO.

CONCRETE-CHUTE DISTRIBUTING SYSTEM.

1,418,738.

Specification of Letters Patent. Patented June 6, 1922.

Application filed August 7, 1920. Serial No. 401,880.

To all whom it may concern:

Be it known that I, JOHN F. ROBB, a citizen of the United States, residing at Cleveland Heights, in the county of Cuyahoga 5 and State of Ohio, have invented certain new and useful Improvements in Concrete-Chute Distributing Systems, of which the following is a specification.

The most modern and now almost universally used method of distributing concrete for the erection of buildings, building of walls, and similar concrete or reinforced concrete structures involves the employment of a central tower elevating means for elevating the concrete aggregates to different points depending upon the heights to which the erection has been made, a receiving hopper for the concrete elevated carried in a suitable manner on the tower, and a system of chutes leading from said hopper and supported by a boom or by tackle in a suitable manner. The system of chutes conveys the concrete by gravity to the place where it is to be deposited. The general distributing 25 plant above described is one of the highest efficiency known.

The object of this invention is to improve certain features of the above system of concrete distribution. Especially does the invention relate to the provision of counterbalancing reversely extending chutes connected by a suitably fabricated reinforcing frame and means for directing the concrete materials to either one or the other of said 35 reversely extending chutes according to the direction in which the concrete is to be conveyed, and at the will of those in charge of the apparatus.

More specifically the invention improves upon the counterbalance chute construction of what is known as the "Insley System" of concrete distribution, comprising a frame supporting a chute leading off in one direction and a weight supported by the opposite 45 end of the frame to counter-balance the chute and materials passing therealong in the distributing operation.

Additionally the invention involves peculiar revolving supporting means for the reversely extending chute unit, or units, it being contemplated that a series of the latter 50 may be utilized in connection with one another. By the use of the invention where a long line of chuting is in position it becomes unnecessary to disturb the adjustment of said line of chuting when a different 55

line, that of the reversely extending chute is desired to be put into action. A greater radius of distribution is thus obtained without necessitating the readjustment of an especially long line of chutes and a very flexible system is provided. 60

Again my invention includes novel means to control the direction of flow of the concrete, in respect to the reversely extending chutes so that one or the other shall be active, or both of them if necessary or desirable. 65

These improvements furthermore comprehend the employment of an adjustable weight, if necessary or desirable, so coacting with the chute frame as to assist in counterbalancing either one or the other of the reversely extending chutes. 70

In the accompanying drawings, 75

Figure 1 is a side elevation of a concrete distributing system embodying the invention.

Figure 2 is an enlarged view partly in section and partly in elevation, showing more clearly the mode of suspension of the reversely extending chute units and bringing out the reversely adjustable valve. 80

Figure 3 is a section taken out on the line 3-3 of Figure 2. 85

Figure 4 is a view in elevation of one of the chute units.

Figure 5 is a combined view showing a series of diagrammatic adjustments of the chute units relatively to the central elevating tower. 90

The invention hereof is of such simplicity as to require very brief description to enable those versed in this particular art to understand the improvements as set forth. 95 Referring to the main figures of the drawings the central distributing and elevating tower for the concrete is illustrated at A. Supported on this tower, and adapted for vertical adjustment as required, is the hopper B. The elevator or hoist by which the concrete is raised and transferred to the hopper B is not shown but may be of any usual type. Leading from the hopper B is a supporting part comprising the distributing chute 1. This chute is supported at its upper end by a suitable rotative connection with the hopper B, and the chute may also be raised vertically by movement about a horizontal axis. The boom 2 and the tackle, shown at 3 and 4, support the chute 1 at the lower end in the known manner. 100 105 110

Suspended from the chute 1 at its lower end, is a chute unit of my invention. The unit is designated C and comprises a fabricated framework 5, of somewhat triangular shape and suitably reinforced to make it rigid; additionally said unit includes, practically as a part of the framework, the reversely extending chutes 6 which meet or merge into one another at their upper ends 10 at the hopper 7. A ring 8, swiveled on the lower end of the chute 1, has connected therewith the links 9 which are attached to the hopper 7, and in this way the chute unit C is rotatively and pivotally connected with 15 the chute 1.

Figure 2 plainly shows how I provide a gate for valve 10, movable to opposite adjustments whereby to direct the concrete passing from the chute 1 to the hopper 7, 20 into either one of the chutes 6. The valve 10 may be adjusted to a midway or central position in the hopper 7 and in this way the concrete may be directed into both chutes 6 to flow in opposite directions to spaced distributing points. Any suitable means, such 25 as a spring contrivance 11, may be employed to hold the valve or gate 10 in its central position and gravity resorted to to maintain the valve in either of its oppositely inclined 30 positions.

I contemplate using manipulative ropes or cords 12 connected with the valve 10 and extending to opposite ends of the unit C, for operating said valve at the will of the user 35 of the apparatus.

At each end of the unit C other units C' may be arranged at opposite ends, or one end of the unit C, or a line of chutes or spouting may be connected with either or 40 both such ends as will be well understood by those versed in this art.

If desired I may use adjustable chutes such as designated at 13, for the units C'.

If desired I may employ an adjustable 45 weight 14 equipped with rollers and shiftable on a horizontal bar 15 and adapted to be held in place by suitable fastening means 16 at various adjustments, so that if one chute 6 of the unit C is used the weight of 50 the concrete received thereby may be counterbalanced by the weight 14, which may be shifted from one side to the other of the vertical axis of the hopper 7, or positioned in line with said axis.

It is contemplated within the purview of 55 this invention to use tackle 1 for supporting the chute 1 and one or more of such units as are shown at C.

By the use of the invention it is clear that 60 one end of the customary triangular frame at present used to support one chute of the distributing system, is made useful as a support for a reversely extending chute, thereby increasing the usefulness of the apparatus 65 without materially increasing the ex-

pense of structure because the provision of the additional chute is very little more structurally than would be the fabricated metal of said frame. Of greater importance however, is the wider radius of action afforded by the system.

Having thus described my invention what I claim as new is:

1. In combination, a main distributing chute, and a chute unit communicating with the main distributing chute, said chute unit comprising oppositely extending counterbalancing chutes connected at adjacent ends.

2. A construction substantially as claimed in claim 1 wherein the oppositely extending chutes of the chute unit are supported at their connected ends and downwardly inclined from each other.

3. A construction as claimed in claim 1, combined with chutes leading from the oppositely extending chutes of the chute unit.

4. A construction as claimed in claim 1 wherein the chute unit is rotative relatively to the main distributing chute.

5. A construction substantially as claimed in claim 1 combined with connecting means intermediate to the chute unit and the main distributing chute and comprising a universal connection.

6. A construction substantially as claimed in claim 1, combined with means for causing concrete flowing through the main chute to pass to either of the oppositely extended chutes of the chute unit.

7. A construction substantially as claimed in claim 1, in which the chutes incline downwardly, combined with means for causing the concrete passing through the main chute to be directed into both of the chutes of the chute unit.

8. A construction substantially as claimed in claim 1 combined with means for causing concrete passing through the main chute to be directed to either one or both of the oppositely extended chutes of the chute unit.

9. In combination a concrete elevating and distributing means including a hopper, a main distributing chute leading from the hopper, a triangular chute unit supported by the main distributing chute, and comprising opposite downwardly extending counterbalancing chutes connected together at adjacent ends and communicating with the main chute.

10. A construction substantially as claimed in claim 9, combined with means for varying the counterbalancing effect of one chute relatively to the other of the chutes of the chute unit.

11. A construction substantially as claimed in claim 9, combined with a weight shiftable to occupy a position in line with the vertical axis of the chute unit or at either of opposite sides thereof.

12. A construction as claimed in claim 9,

combined with a triangular chute unit supported at one end of the first named chute unit and of similar construction.

13. A chute unit for concrete distributing systems including oppositely extending communicating chutes and a reinforcing frame therefor, and means to direct concrete to either chute.

14. In combination, a central distributing tower, and a system of distributing chutes supported thereon, comprising a main distributing chute, and a chute unit suspended at the lower end of the main distributing chute, said chute unit comprising oppositely extending, counterbalancing chutes connected at adjacent ends; and connected with the main chute at said adjacent ends, and a

chute connected with one of the oppositely extending chutes of the chute unit.

15. In combination a concrete elevating and distributing means including a hopper; a main distributing chute leading from the hopper, a triangular chute unit supported by the main distributing chute, and comprising opposite downwardly extending counterbalancing chutes connected together at adjacent ends and communicating with the main chute and rotatively supported thereby, and units rotatively supported at each end of that first mentioned and of like construction to receive materials therefrom.

In testimony whereof I affix my signature.

JOHN F. ROBB.
